(57) **CLAIM**

The ornamental design for a metal and polymeric container lid, as shown and described.

DESCRIPTION

FIG. 1 is top perspective view of an embodiment of a container lid showing our new design;

FIG. 2 is a partial cross-sectional view of the container lid taken in the direction of line 2-2 of FIG. 1;

FIG. 3 is a top plan view of the container lid;

FIG. 4 is an elevational view of a side of the container lid, all side views of the container lid being substantially identical;

FIG. 5 is a bottom perspective view of the container lid;

FIG. 6 is a bottom plan view of the container lid;

FIG. 7 is top perspective view of another embodiment of a container lid showing our new design;

FIG. 8 is a partial cross-sectional view of the container lid taken in the direction of line 8-8 of FIG. 7;

FIG. 9 is a top plan view of the container lid;

FIG. 10 is an elevational view of a side of the container lid, all side views of the container lid being substantially identical;

FIG. 11 is a bottom perspective view of the container lid; and,

FIG. 12 is a bottom plan view of the container lid.

In FIG. 1 and FIG. 7, the broken line arrows represent sectional designations that form no part of the claim.

The broken lines shown herein depict portions of the metal and polymeric container lid that form no part of the claimed design. For clarity, the alternating heavy and light line crosshatching in the partial cross-sectional views is used to illustrate the polymeric material components, and the consistent light line crosshatching in the partial cross-sectional views is used to illustrate the metal material components, which forms a part of the claimed design.
